(57) **CLAIM**

The ornamental design for a waste removal mitten, as shown and described.

DESCRIPTION

FIG. 1 is an environmental perspective view of the waste removal mitten, showing the new design;

FIG. 2 is an isolated perspective view of the waste removal mitten thereof;

FIG. 3 is a front elevational view of the waste removal mitten thereof;

FIG. 4 is a rear elevational view of the waste removal mitten thereof;

FIG. 5 is a left side elevational view of the waste removal mitten thereof;

FIG. 6 is a right side elevational view of the waste removal mitten thereof;

FIG. 7 is a top plan view of the waste removal mitten thereof; and,

FIG. 8 is a bottom plan view of the waste removal mitten thereof.

The broken lines in the drawings illustrate environmental subject matter and form no part of the claimed design.

1 Claim, 3 Drawing Sheets
